UNITED STATES PATENT OFFICE.

JAMES W. EGGLESTON, OF CHICAGO, ILLINOIS, ASSIGNOR OF ONE-THIRD
TO SPENCER STILLWELL & COMPANY, OF NEW YORK, N. Y.

PRINTER'S INK-FOUNTAIN.

SPECIFICATION forming part of Letters Patent No. 763,866, dated June 28, 1904.

Application filed September 10, 1903. Serial No. 172,672. (No model.)

To all whom it may concern:

Be it known that I, JAMES W. EGGLESTON, a citizen of the United States of America, and a resident of Chicago, in the county of Cook and State of Illinois, have invented certain new and useful Improvements in Printers' Ink-Fountains, of which the following is a specification.

This invention relates to printers' ink-fountains, and it includes certain improvements in the means for supplying ink to the ordinary rotary ink-distributing plate which may be summarized as follows: first, the employment in an ink-reservoir of a snugly-fitting spring-pressed plunger to force the ink-supply through an adjustable exit-orifice with mechanical means for removing said plunger when desired to recharge the reservoir; second, a feed-roller intermediate the reservoir-exit and the inking-plate, said roller being shaped as the frustum of a cone to present opposite parallel surfaces relatively with the horizontal base of the ink-reservoir and the inclined surface presented by the inking-plate; third, simple, practical, and economical means of constructing the several parts comprising the ink-fountain and the various devices for connecting it to a printing-press, together with means for positively and accurately adjusting its relative position and that of the feed-roller with relation to the inking-plate.

In the drawings accompanying this application, Figure 1 is a perspective elevation of my improved ink-fountain, including a rotary ink-distributing plate with inking-rollers of the usual character disposed thereover, this view showing the general operative relative arrangement of the invention in conjunction with a printing-press. Fig. 2 is a vertical sectional view taken centrally through Fig. 1. Fig. 3 is a detail sectional view taken on the line $\alpha\alpha$ of Fig. 2 and showing, broken away, the arm for connecting the apparatus to a printing-press; and Fig. 4 is a detail sectional view taken on the line $\gamma\gamma$ of Fig. 2, showing

the relative arrangement of the ink-feeding exit and roller.

In the figures the numeral 1 indicates the ordinary rotary ink-distributing plate of a printing-press, partly broken away, and 50 shown as disposed at approximately the usual inclination.

Suitably supported in a manner to be referred to hereinafter above the plate 1 is an ink-reservoir 2, having an outlet 3 in its base 55 and a valve 4 adapted to close or regulate said outlet. The reservoir 2 is preferably cup-shaped and the upper portion of its interior wall produced in smooth cylindrical form, terminating at its lower end in an annular seat 5, 60 located at a point above the base of the reservoir. A cap 6 is adapted to cover the reservoir and has an annular depending flange 7 to fit snugly about its wall, screws, as 8, being passed through tapped holes therefor in the 65 flange and wall to securely fasten the cover upon the reservoir. While only one of said screws 8 is shown in the view presented, it will be readily understood that two or more may be provided about the circumference of the 70 reservoir, or said cap may be securely adjusted in position by other suitable means. The cap 6 is provided with a central boss or extension, as 9, which is provided with a smooth vertical aperture, through which is 75 loosely passed a threaded stem 10, bearing an adjustment-nut 11 exterior to the boss 9 to limit its degree of entry within the reservoir and being connected at its inner end to a pressure-plunger, as 12. Said plunger 12 preferably consists of a flat disk whose circumference corresponds to the interior horizontal diameter of the cylindrical portion of the reservoir, having a liquid-tight movable relation therewith in the manner of a piston-head within a 80 cylinder. The stem 10 is preferably connected to plunger 12 by screwing into a threaded boss 13 upon the upper surface thereof.

Placed about stem 10 within the reservoir is a spiral spring 14, bearing at its opposite 90

ends, respectively, against the cap 6 and plunger 12 and being capable of exerting pressure to force said plunger downwardly until the latter becomes seated upon the annular shoulder 5, or the downward travel of plunger 12 may be limited to a point anterior to such shoulder 5 by a suitable adjustment of the take-up nut 11. The reservoir is supported by being held with its thickened portion 15 against a vertical arm 16, to which it is secured by a screw 17, passed through a vertical slot 18 in arm 16, and having a head 19, that bears against opposite sides of said slot. Thus by loosening screw 17 the reservoir may be adjusted vertically upon arm 16. As a means of supporting the reservoir when screw 17 is loosened and of adjusting its vertical position I tap a vertical hole in the thickened portion 15 and screw therein a vertical rod 20, locking said rod therein by a set-screw 21, entered laterally into portion 15 and impinging against the threads on rod 20. The arm 16 is furnished at its upper end with the upper and lower horizontally-extending vertically-slotted fingers 22 22, the rod 20 being entered within the slots thereof and carrying intermediate said fingers a knurled adjustment-nut 23. As the upper and lower ends, respectively, of nut 23 are in close relation to the fingers 22 22, it is obvious that the effect of turning said nut in either direction is to move vertically the rod 20, and consequently the reservoir, in a corresponding direction.

Within a lower extension of the arm 16 is journaled a shaft 24, carrying a sleeve 25, upon which is mounted a concentric pad or feed-roller, as 26. Because it is desirable that the exit-orifice from the reservoir to the feed-roller should be in a horizontal plane, to permit of an even flow of ink over the width of said roller, and because the roller, which is disposed intermediate said exit-orifice and the inclined distributing-plate, must present its surface in parallel planes to both said elements, I therefore form the exterior contour of feed-roller 26 as the frustum of a cone, as seen, its surface at opposite points thus being in parallel relation, respectively, with both said divergent planes, and this formation of roller preventing dragging occurring in the frictional rotation communicated from the plate 1 to roller 26. A vertical rod 27 is secured to the arm 16, as by rings or lugs 28 28, and a sleeve member 29, carrying a hanger 30, is adjustably mounted upon said rod, a set-screw 31 serving to secure said sleeve in its adjusted position. The hanger 30 extends at right angles from rod 27 and is provided with an elongated vertical slot 32 to receive a bolt 33 wherewith to adjustably connect one end of a curved supporting-bracket 34, the opposite end 35 of said bracket being suit-

ably supported to a portion of the frame of the printing-press.

In the operation of my invention, the parts 65 being adjusted as indicated in Fig. 2 and the reservoir 2 being partly filled with ink, the plunger 12 is seen to be pressing under the tension of spring 14 to force a supply through the slotted orifice 3. The rotary plate 1, frictionally turning the roller 26, causes the latter to receive from said slotted orifice by capillary attraction, aided by the spring-pressure before referred to, an even supply of ink over its entire surface. This supply is 75 then continuously applied to the plate 1 evenly to an extent corresponding to the width of roller 26, after which it is distributed in the usual manner by the usual inking-rollers.

In order to remove plunger 12 for the purpose of recharging the reservoir, the nut 11 is turned downwardly upon stem 10, thereby serving to draw the plunger to the upper end of the reservoir, where it can be easily removed after releasing the cap 6.

The means of adjusting the vertical position of the reservoir relatively to the roller 26 and the means of vertical and lateral adjustment of the entire apparatus relatively to the printing-press are all clearly shown and 90 will be readily understood from the foregoing description.

Having now described my invention, I declare that what I claim is—

1. The combination in a printer's ink-fountain, of a reservoir having a slotted base-exit and a valve to regulate same, a spring-pressed plunger to force ink through said exit, and a feed-roller to receive ink therefrom.

2. In a printer's ink-fountain a cylindrical reservoir having a base-outlet, a horizontally-disposed, vertically - movable liquid - tight plunger therein, a cap for said reservoir having a central orifice, means for securing said cap upon the reservoir, a threaded plunger-stem loosely passed through said orifice, a spring to depress said plunger, and an adjustment-nut upon said stem to withdraw said plunger.

3. In a printing-press, the combination with a rotary distributing-plate disposed at an inclination, of an ink-reservoir supported above said plate and having a horizontal outlet, a feed-roller intermediate said plate and said outlet, and said feed-roller being shaped as the frustum of a cone, to present opposite, parallel adjacent surfaces, respectively, to the outlet and the plate, and means rotatably supporting said roller.

4. In a printing-press, the combination with a rotary distributing-plate, of a reservoir having a slotted outlet and a valve to regulate same, a feed-roller intermediate said plate and reservoir, a support for said reservoir and

roller, and means for adjusting the former vertically with respect to the latter.

5. In a printing-press, the combination with a rotary distributing-plate, of a reservoir, a feed-roller intermediate said plate and reservoir, an upright, vertically, slotted support, a journal bearing in said support for said roller, a headed adjustment-screw passed through said slot into the wall of the reservoir, and a ver-

tical, threaded rod secured to the reservoir, 10 said rod bearing an adjusting-nut with means for preventing its vertical movement.

Signed at New York this 17th day of June, 1903.

JAMES W. EGGLESTON.
